UNITED STATES PATENT OFFICE.

OLIVE M. SIMPSON, OF WASHINGTON, DISTRICT OF COLUMBIA.

DESIGN FOR AN IMAGE.

43,907.

Specification for Design.

Patented Apr. 22, 1913.

Application filed February 16, 1912. Serial No. 678,081. Term of patent 3½ years.

To all whom it may concern:

Be it known that I, OLIVE M. SIMPSON, a citizen of the United States, residing at Washington, District of Columbia, have invented a new, original, and ornamental Design for Images, of which the following is a specification, reference being had to the accompanying drawing, forming part thereof.

Fig. 2 is a side elevation of the image.

I claim:

The ornamental design for an image as shown.

OLIVE M. SIMPSON.

Witnesses:

C. E. FETZER,
L. E. BOBYS.
